I claim the ornamental design for a magnifying device, as shown and described.

DESCRIPTION

FIG. 1 is a perspective view of a magnifying device in an expanded configuration, as viewed from the top and one side thereof.

FIG. 2 is a top plan view of the magnifying device of FIG. 1 in the expanded configuration.

FIG. 3 is a first side elevation view of the magnifying device of FIG. 1 in the expanded configuration.

FIG. 4 is a front elevation view of the magnifying device of FIG. 1 in the expanded configuration.

FIG. 5 is a bottom plan view of the magnifying device of FIG. 1 in the expanded configuration.

FIG. 6 is a back elevation view of the magnifying device of FIG. 1 in the expanded configuration.

FIG. 7 is a second side elevation view of the magnifying device of FIG. 1 in the expanded configuration.

FIG. 8 is a bottom plan view of the magnifying device of FIG. 1 in a collapsed configuration; and,

FIG. 9 is a top plan view of the magnifying device of FIG. 1 in the collapsed configuration.

The details shown in broken lines are for illustrative purposes only and form no part of the claimed design.
